WALTER VAN BRAAM ROBERTS, OF PRINCETON, NEW JERSEY, ASSIGNOR TO RADIO CORPORATION OF AMERICA, A CORPORATION OF DELAWARE

SIGNALING METHOD AND MEANS THEREFOR

Application filed October 4, 1928. Serial No. 310,240.

This invention relates to a method of signaling and means therefor, and more particularly to a signaling system radiating a modulated radio frequency wave.

During the reception of a broadcast signal it is often noticed that when a soft passage is received there is a great deal of hiss and noise. During the reception of a loud passage, this hiss and noise are drowned out. The first mentioned effect is due to the relative weakness of side frequencies caused by small percentage of modulation. The carrier, being of constant amplitude, heterodynes stray noises as loudly during weak passages as it does during loud ones.

This invention has, for one of its objects, the reduction of these objectionable noises during the reception of soft signals. This is done by maintaining the average percentage of modulation approximately constant for both soft and loud signals and simultaneously varying the strength of all components of the radiated energy so that at a receiver the same effect as that of a constant amplitude carrier, modulated by a variable amplitude signal, is obtained.

In the accompanying drawings which show ways of carrying out the main object of this invention, Figure 1 shows diagrammatically apparatus for maintaining the modulation of the output of an oscillator constant and for simultaneously varying the amount of energy radiated from the oscillator and Figure 2 shows apparatus for carrying out the functions of the apparatus of Figure 1 automatically.

Referring to Figure 1, 1 indicates a microphone, 2 an audio frequency amplifier, 3 a modulator tube, 4 an oscillator, 5 a radio frequency amplifier, and 6 a radiating antenna. A leverage system 7, 8, 9 which may be actuated manually is provided for simultaneously varying the amplification of the audio frequency amplifier 2, for example, by altering coupling or grid bias; and, the input to radio frequency amplifier 5, for example, by altering the coupling to 5. A voltmeter V is placed in the output circuit of amplifier 2 to indicate the voltage applied to the control electrode of tube 3.

The leverage system 7, 8, 9 should be arranged and manipulated so that the average output voltage of amplifier 2 as indicated by V is kept substantially constant and so that the power output of radio frequency power amplifier 5 is varied in an inverse sense relative to the manner in which the audio frequency signal 2 is amplified by amplifier 2. Adjustments of the control system which increase the amplification of audio amplifier 2 simultaneously decrease the potentials applied to the power amplifier 5, and vice versa. In this way, although the per cent of modulation of oscillator 4 remains constant, the reverse variation of the power radiated causes the same effect to be obtained at a receiver as though ordinary variable modulation of a constant carrier were utilized, but without the hiss present when the latter method of transmission is made use of.

The operation of the system shown in Figure 1 may be explained mathematically as follows. Assume that the microphone output voltage is E and the audio frequency amplification of amplifier 2 is A. Then the audio frequency input to modulator tube 3 is AE. If the frequency of the audio current is F, then the modulated radio frequency current will vary in amplitude approximately as $(1+KAE \cos F)$ where K is a constant. The radiated field is given by the expression $H \cos Y (1+KAE \cos F)$ where H is proportional to the antenna current and Y is proportional to the carrier radio frequency.

At the receiver the current of frequency F in the loud-speaker depends upon $H^2 AE$. Therefore, if A is adjusted to keep AE substantially constant, the leverage mechanism 7, 8, 9 should be manipulated in such a manner, that $H^2 A$ is not altered by the operation of the leverage mechanism.

One advantage of my system described above is that less power is required on the average to radiate a given program or signal.

Figure 2 shows apparatus for automatically varying the amplification of the audio frequency signals to be transmitted and for varying the amount of modulated high frequency energy radiated. An additional am-

plifier 10 is provided which may be connected across the input side of amplifier 2. The output of amplifier 10 is fed into a rectifier 11. The direct current output of rectifier 11 which will vary in accordance with the loudness of the signals impressed on microphone 1 is fed through amplifier 12 into solenoid 13. According to the strength of the input to microphone 1 solenoid 13 magnetically draws on plunger 14 against the pull of spring 15 whose tension may be adjusted as found desirable. Levers 7 and 9 are thus automatically adjusted by intercalating elements 16, 17 fastened to plunger 14 and link 8 respectively.

Members 16 and 17 are made to interfit so as to allow for the relative vertical movement of link 8 caused by the angular movement of links 7 and 9. Lever 9 is caused to actuate the rotors of condenser 18 whose capacity is varied in order to change the input to power amplifier 5. The plates on condenser 18 may be cut so that for a given amount of audio amplification by amplifier 2 a desired or predetermined amount of modulated radio frequency energy is radiated.

It is to be noted that the system is designed to operate on average changes in amplitude of low frequency signals and does not respond to rapid changes such as a sudden high note or, when for example a short burst of applause is radiated. Furthermore, if it is desired to broadcast signals in the ordinary fashion, all that is necessary is, in Fig. 1 to hold stationary the leverage system, and in Fig. 2, to disconnect the solenoid 13, for example, by disconnecting the input to amplifier 10.

Although the embodiments illustrated in the accompanying drawings disclose the principles of my invention and ways in which they may be carried out successfully in practice, it will be apparent that various minor changes will readily suggest themselves to those skilled in the art. Accordingly my invention is not to be limited by the modifications shown but on the other hand is to be given the scope and breadth indicated in the appended claims.

50 50 What I claim as my invention is:

1. The method of radiating a low frequency signal by modulating high frequency energy therewith which includes varying the amplification of the low frequency signal so that the average percent of modulation of the high frequency energy shall remain substantially constant, and simultaneously relatively varying the strength of the energy radiated in a manner opposite in sense relative to the manner in which the amplification of the low frequency signal is varied.

2. The method of radiating low frequency currents by modulating high frequency energy therewith which includes automatically varying the amplification of the low fre-

quency currents so that by modulating the high frequency carrier energy therewith the average percent of modulation of the carrier energy remains substantially constant, and automatically reactively varying the amount of energy radiated in an opposite sense relative to the manner in which the amplification of the low frequency signal is varied.

3. The method of radiating a signal of varying amplitude which includes variably amplifying the signals to a substantially constant average value, modulating a carrier energy by the constant value amplified signal and simultaneously reactively controlling in inverse sense to the amplification variation, the amount of carrier energy radiated.

4. In a radio signaling system means for amplifying a signal of variable amplitude to a substantially constant value, means for modulating carrier energy by the constant value amplified signal, and means for reactively controlling in inverse sense to the amplification, the amount of radiated carrier energy.

5. In a radio signaling system means for amplifying in a predetermined manner a signal of variable amplitude, means for modulating carrier energy by the amplified signal energy, and means for reactively controlling in inverse manner relative to the amplification of the modulated carrier energy, the amount of modulated carrier energy radiated.

6. In combination, a source of signal energy, a source of carrier energy, means for modulating carrier energy with the signal energy, an antenna, a variable reactance between the antenna and modulating means to control the amount of carrier energy radiated, and means for varying the reactance inversely to the strength of the signal energy.

7. In a system for transmitting or conveying intelligence from one geographically situated point to another geographically situated point, by means of propagated electromagnetic waves derived from the flow of undulatory electrical currents operated upon in accordance with the intelligence to be transmitted, an electron discharge device having an evacuated container wherein are contained an electron emitting cathode, an anode, and a grid interposed between the anode and cathode, means for subjecting the electrodes within said container to high frequency undulatory electrical potentials, an output circuit for said electron discharge device, and, means for controlling the amount of high frequency energy in said output circuit, said means comprising a variable condenser.

8. In an electrical system of the character described, the combination of an electron discharge device having an anode, a cathode and a control electrode, each of said electrodes being subjected to high frequency poten-

tials, a tunable output circuit for said electron discharge device, and, a variable condenser for controlling the amount of high frequency energy present in said tunable output circuit.

9. In a wireless signaling system in which a carrier frequency is modulated by a signal frequency, the combination with a modulator of a source of carrier frequency, a source of signal frequency, both said sources being operatively connected to the modulator, a transmitting antenna system variably coupled to said modulator, an amplifier circuit having its input coupled to said source of signal frequency and its output coupled to the input of a rectifying system and means coupled to the output of the rectifying system for controlling the amount of signal energy fed from said source of signal frequency 20 to said modulator and for varying the coupling between said antenna system and said modulator.

10. In a wireless transmission system in which a carrier frequency is modulated by amplified signal energy, the method of reducing the effect of interference and at the same time maintaining the proper relation between the received signals and the signals desired to be transmitted which comprises 25 variably amplifying the signal energy in a sense so as to maintain the voltage thereof approximately constant, modulating the carrier frequency with the said approximately constant voltage signal energy and variably 30 transmitting the resulting energy said variations being in opposite sense to the variations of amplification made upon said signal energy.

11. The method of transmitting signals 40 by means of a carrier wave which is modulated by amplified signals which comprises varying simultaneously but in opposite sense the amount of signal amplification and the transmission gain of the entire modulated 45 wave between the modulating devices and the radiator.

12. In a wireless transmission system in which a carrier frequency is modulated by amplified signal energy, the method of reducing the effect of interference and at the 50 same time maintaining proper relationship between signals desired to be transmitted and received signals which comprises variably amplifying the signal energy in a sense 55 to maintain the voltage thereof approximately constant, modulating the carrier frequency energy with the approximately constant voltage signal energy and varying the amount of the resulting modulated carrier 60 frequency energy radiated into the ether simultaneously but in opposite sense to the variations of amplification made upon said signal energy.

13. In a wireless signaling system in which 65 the carrier frequency is modulated by sig-

nal energy, the combination with a modulator of a source of carrier frequency, a source of signal energy, both said sources being operatively connected to the modulator, said source of signal energy being 70 connected to said modulator through an amplifying circuit, means in said amplifying circuit for varying the amount of amplification of said signal energy, an antenna system variably coupled to said modulator, 75 said coupling having means for controlling the amount of modulated carrier frequency energy allowed to pass from said modulator to said antenna system, a coupling device connected to both said means and adapted to 80 vary them simultaneously and in opposite sense.
